FRANCIS M. HENRY AND JOHN M. POWERS, OF MINNEAPOLIS, MINNESOTA.

NUT-LOCK.

No. 829,209.

Specification of Letters Patent. Patented Aug. 21, 1906.

Application filed April 14, 1905. Serial No. 256,495.

To all whom it may concern:

Be it known that we, FRANCIS M. HENRY and JOHN M. POWERS, of Minneapolis, Hennepin county, Minnesota, have invented certain new and useful Improvements in Nut-Locks, of which the following is a specification.

The object of our invention is to provide means for securing a nut on a bolt which will permit the removal of the nut at any time without the use of special tools.

A further object is to provide a nut-lock that will be simple and inexpensive to manufacture and one that will be strong and durable and easily and quickly manipulated to lock or unlock the nut.

The invention consists generally in various constructions and combinations, all as herein-after described, and particularly pointed out in the claims.

In the accompanying drawings, forming part of this specification, Figure 1 is a view of a bolt and nut, partially in section, showing the position of the locking flange or tongues on the nut. Fig. 2 is a sectional view of the bolt, showing the flattened locking-surface thereon. Fig. 3 is a similar view showing the flange pressed down upon the flat surface of the bolt. Fig. 4 is a sectional view showing a shoulder formed on one side of the flat surface of the bolt. Fig. 5 illustrates a locking-tongue pressed down upon the shoulder. Fig. 6 is an enlarged sectional view showing the manner of raising the tongue from the flat surface by partially revolving the nut. Fig. 7 is a similar view showing the locking-tongue raised sufficiently to clear the shoulder on the bolt.

In the drawings, 2 represents a bolt having threads 3 at one end and a flat surface 4, which on one side is rounded off and merges into the threads of the bolt, the other side being left flat, as indicated in Fig. 2.

5 represents a nut having a flange 6 on one side, that may be of the form of a continuous ring extending around the bolt, as shown in Fig. 2. To lock the nut, this ring is struck with a hammer or other tool and a portion of it forced down upon the flat surface, as shown in Fig. 3. We may prefer, however, to divide this flange into a series of tongues 7, that project from the nut and may be forced down independently of one another upon the flat surface. These tongues may be formed in various ways on the nut; but probably as economical a method as any would be to di-

vide the annular flange or ring 6 by a series of saw-cuts. When one of these tongues has been forced down upon the flat surface, the nut will be securely locked. If, however, it is desired to release the nut, it is turned toward the right, and the depressed tongue following the curved surface will ride up onto the threads and be lifted sufficiently to clear the flat surface when the nut is turned in the opposite direction. To insure the locking of the nut, we may prefer to provide a shoulder 8 on the flat surface that will be in the path of the locking-tongue and positively prevent the nut from turning toward the left until the tongue has been raised sufficiently to clear the shoulder. When this shoulder is used, its corner may be beveled, as shown in Fig. 7, and a similar bevel may be provided on the edges of the tongues, so that when the nut is being removed the tongue will ride over the shoulder without catching thereon, having previously been raised off the flat surface by the rotation of the nut toward the right. The use of this form of lock-nut with the curved surface on the bolt merging into the threads permits us to dispense with the use of all special tools usually required for unlocking nut-locks of this type. A track-walker or section-man with an ordinary wrench by simply rotating the nut toward the right can raise the tongue a sufficient distance to clear the flat surface or the shoulder and allow the nut to be removed from the bolt, or if it is merely necessary to tighten the nut the workman can turn it toward the right sufficiently to tighten it and then force down another tongue upon the flat surface to lock the nut in its new position.

We claim as our invention—

1. The combination with a bolt having a threaded end and a flat surface extending on said bolt across the threads lengthwise of the bolt and in a plane substantially at right angles to the radius of the bolt, the threads on one side of said flat surface gradually decreasing in depth as they approach said surface and finally merging therein in a gradual curve and forming a convex continuation of said flat surface on one side thereof, of a nut having an annular flange on one end adapted to be forced down at any desired point in its circumference upon said flat surface and lock said nut against accidental movement, the depressed portion of said flange being raised sufficiently by engagement with said convex surface when the nut is turned to tighten it

on the bolt to clear the said surface when the nut is turned backward to loosen it on the bolt whereby the nut can be locked on the bolt and tightened thereon to allow another portion of said annular flange to be forced down upon said flat surface or the nut removed from the bolt without the use of special tools, substantially as described.

2. The combination, with a bolt, having a threaded end and a flat surface extending on said bolt across the thread lengthwise of the bolt and in a plane substantially at right angles to the radius of the bolt, the threads on one side of said flat surface gradually decreasing in depth as they approach said surface and finally merging therein in a gradual curve and forming a convex continuation of said flat surface on one side thereof, said bolt being provided on the opposite side of said surface with a low stop having a shoulder facing said surface and extending lengthwise thereof on said bolt, of a nut having an annular flange

on one end adapted to be forced down at any desired point in its circumference upon said flat surface and lock said nut against accidental movement, the depressed portion of said flange being raised sufficiently by engagement with said convex surface when the nut is turned to tighten it on the bolt to clear the said surface and the shoulder of said stop when the nut is turned backward to loosen it on the bolt, whereby the nut can be locked on the bolt and tightened thereon to allow another portion of said flange to be forced down upon said flat surface or the nut removed from the bolt without the use of special tools, substantially as described.

In witness whereof we have hereunto set our hands this 7th day of April, 1905.

FRANCIS M. HENRY.
JOHN M. POWERS.
